UNITED STATES PATENT OFFICE.

AUGUST J. BERG, OF CHICAGO, ILLINOIS.

AUTOMATIC-DROP WHEEL-GUARD.

1,317,678.

Specification of Letters Patent.

Patented Oct. 7, 1919.

Application filed October 1, 1918. Serial No. 256,490.

To all whom it may concern:

Be it known that I, AUGUST J. BERG, a citizen of the United States, residing at Chicago, in the county of Cook and State of Illinois, have invented a new and useful Automatic-Drop Wheel-Guard, of which the following is a specification.

My invention relates to wheelguards secured to the front end of motor vehicles and which are automatically dropped when an object contacts with the tripping apron which is hung in front of the wheelguard, and the objects of my improvements are first, to automatically drop the rear edge of the inner part of the cradle simultaneously with the front edge thereof; second, to enable varying the distance that the rear edge drops irrespective of how far the front edge drops; third, to provide means for preventing the cradle swaying up and down with respect to the car; fourth, to economize on the construction; fifth, to make a simple, efficient and durable construction and other features to become apparent from the description to follow.

Wheelguards as heretofore made have been arranged to be dropped automatically when an object contacted with the tripping apron, but when the front edge of the cradle was thus dropped to the roadway the slope or inclination of the same was so abrupt that any object which may have been caught up on the cradle would tend to slide or roll down toward the front edge of the cradle, further more as the vehicle is suddenly brought to a stop the momentum of the object on the cradle also tends to cause said object to slide or roll forward off the front edge of the cradle. Another undesirable feature is that when the cradle is dropped to the ground the front edge of the cradle is liable to catch against any obstruction protruding above the roadway and thus be damaged or broken. By the use of my invention the cradle when dropped is on such a slight incline that there is very slight or no tendency for an object on the cradle to slide or roll toward the front edge of the same and the cradle always tends to slide over any obstruction protruding above the roadway.

To describe my invention so that others versed in the art to which it pertains can make and use the same, I have illustrated it on the accompanying sheet of drawing form-

ing a part of this specification, and in which:

Figure 1 is a central longitudinal section of a wheelguard embodying my invention showing the cradle in its normal upper position; Fig. 2, is a similar view showing the cradle dropped to the roadway and Fig. 3, is a fragmental plan view showing the construction of the cradle.

Similar reference characters refer to similar parts throughout the several views.

The platform timbers of a vehicle are indicated at 4 to which the depending supports 5 and 6 are secured. A cross shaft 7 is rotatably mounted in supports 6, and on said shaft loosely hangs the tripping apron 8 by means of hooks 9.

As clearly shown in Fig. 1, if the lower end of the apron 8 is swung to the left the hook 9 will contact with pin 10, which extends laterally from the free end of arm 11 made rigid to shaft 7, and will partly rotate said shaft 7 clockwise. The forward end of the operating or adjusting rod 11' is pivotally connected at 12 to the free end of arm 13 rigidly secured to shaft 7. In its normal position as seen in Fig. 1, the operating or adjusting rod 11' tends to push forward toward the shaft 7, but is prevented from moving forward because the pivot 12 is slightly below the plane of the center of shaft 7, and the shaft is prevented from turning counter-clockwise. Thus when the shaft 7 is given a slight turn clockwise by the swinging of the apron 8, the pivot 12 is turned up above the plane of the center of shaft 7, and when the pivot 12 is in such position the operating or adjusting rod 11' is free to move to the right above shaft 7 to assume a position as shown in Fig. 2. To reset or turn the shaft 7 back to its normal position a third arm 14 is rigidly secured to shaft 7 and has pivotally connected to its free end a foot lever 15 which extends upward through a perforation in platform 4. The lever 15 is curved so that a downward pressure of the foot will tend to rotate shaft 7 contra-clockwise from the position shown in Fig. 2, to a position shown in Fig. 1.

Pivoted on the lower end of each support 5 at 16 is an upright 17 having a horizontally disposed hollow extension 18. The uprights 17 are spaced apart and are rigidly secured together by means of a plu-

rality of rods or pipes 19 which form the upright rear portion of the cradle, while the frame for the horizontally disposed portion is formed by a U shaped rod or pipe 22 having its ends secured in the hollow horizontally disposed extensions 18. The bottom or inner part of the cradle is formed of a plurality of slats 20, preferably wood, secured in a spaced apart position by a plurality of flat metal bands 21 which have their forward ends hooked around the straight front part of the rod or pipe 22, so that the said bottom or inner part of the cradle can swing about said rod or pipe as a pivot.

Rigidly secured to the rods or pipes 19 are a pair of arms 23 which extend forward from the uppermost rod or pipe 19 a suitable distance and have their forward extremities extending upward a short distance which are forked and pivotally connected at 24 to the two operating or adjusting rods 11'. The rear ends of the two operating or adjusting rods 11' extend a short distance to the rear of the rods or pipes 19 where they are curved downward and have their extremities connected by means of hooks 25 to the rear edge of the bottom or inner part of the cradle and support the same. The hooks 25 are attached to the rear edge of the cradle bottom or inner part by means of flat metal bands 26 or other suitable means. The flat metal bands 26 are secured to the slats 20 of the cradle bottom or inner part and have their rear ends extended slightly beyond the rear slat where they are provided with a perforation through which the hooks 25 loosely fit. In this manner the entire cradle *i. e.*, the outer frame and the bottom or inner part can be built stock size in large quantities and the metal bands 26 secured in proper position to the slats to fit the particular construction of car to which each wheel guard is to be applied.

It will be noted that in operation the cradle and of course the arms 23 also, swing about the pivots 16, and that when the operating or adjusting rods 11' are in their rear position the front edge of the cradle is held up from the roadway as seen in Fig. 1, and when the operating or adjusting rods 11' are in their forward position the front edge of the cradle is free to drop to the roadway as seen in Fig. 2. The position and length of the arms 23 are such that, when the front end of the cradle is held up from the roadway, the rear edge of the cradle bottom or inner part is held in an elevated position as shown in Fig. 1, and when the front edge of the cradle is permitted to drop to the roadway the rear edge of the cradle bottom or inner part is lowered as shown in Fig. 2. The distance that the rear edge of the cradle bottom or inner part is raised and lowered can be varied

by varying the length of the arms 23. To prevent the cradle from loosely swinging about its pivot 16, I prefer to provide one or more coiled contracting springs 27 connected between the car platform and the rear end 70 of each operating or adjusting rod 11' to yieldingly tend to hold the front edge of the cradle down, and of course also tends to yieldingly hold the operating or adjusting rods 11' in a forward position. While 75 I have shown and described my improved automatic dropping cradle in connection with a wheel guard which is automatically dropped by means of a tripping apron, the same may be employed in connection with 80 any kind of a car fender.

The cradle bottom or inner part may at times become so heavily loaded with dirt, mud or snow and ice that its weight acting through the hooks 25 will pull down on the 85 rear ends of the rods 11' and tend to lift the front ends of the rods 11' to trip the shaft 7. To counteract such overweight of the cradle bottom or inner part, the springs 27 are positioned as shown to partly 90 lift on the rear ends of the rods 11'.

The hooks 25 it will be noted are arranged to have their upper ends pivotally connected to the rear bent down ends of the rods 11', and have the hook part at the lower end extending rearwardly with the straight shank part free to slide through the perforation provided therefor in the bands 26. Thus should the bottom or inner part of the cradle become clogged and refuse to drop freely 100 by its own weight, as it might in case mud and snow accumulated thereon becomes frozen, the front edge of the cradle will be free to drop about the pivots 16; the shanks of the hooks 25 in such event sliding down 105 through the perforations in the metal bands 26.

It will be understood that the size, shape and arrangement of the parts may be varied without in the least departing from 110 the scope of my invention.

Having thus fully described my invention what I claim as new and desire to secure by Letters Patent of the United States is:—

1. In a device of the class described, a 115 cradle mounted on pivots having an outer frame and a bottom or inner part arranged to have its front end swing up and down, an operating or adjusting rod connected at one end to the cradle and at the other end 120 to the free end of a crank arm rigidly mounted on a rock shaft to control the movement of the cradle about its pivots, means for automatically tripping the rock shaft to permit the front edge of the cradle to drop to the roadway and means for resetting the rock shaft comprising a curved foot lever guided by and extending through a hole in the platform of the vehicle.

2. In a device of the class described, a 130

- cradle comprising an outer frame and a bottom or inner part both horizontally disposed, an upright rear portion, the frame of the cradle being pivotally mounted on the vehicle to have the upper end of the rear portion swing forward and back and the front edge of the cradle frame swing down and up, said bottom or inner part of the cradle being pivotally connected to the front edge 5 of the cradle frame to have its rear edge swing up and down relative to the cradle frame, means for dropping the front edge of the cradle frame and means operatively connected to said first named means whereby 10 the rear edge of the cradle bottom or inner part will move up and down simultaneously with the front edge of the cradle frame.
3. In a device of the class described, a cradle comprising a rear upright portion 20 and a horizontally disposed outer frame rigidly connected together and a bottom or inner part pivotally mounted on the front edge of the outer frame, said outer frame mounted on pivots to have the upper part 25 of its rear portion swing forward and backward and the front edge of the outer frame to swing down and up, means for causing the rear edge of the bottom or inner part of the cradle to move down and up simultaneously 30 with the front edge of the outer frame, means for automatically dropping the front edge of the cradle and means for restoring the same to its normal position.
4. In a device of the class described, a cradle mounted on pivots having an outer frame and a bottom or inner part arranged 35 to have its front end swing up and down, said bottom or inner part flexibly connected to the cradle outer frame to have its rear edge free to move up and down with relation 40 to the outer frame, means for automatically dropping the cradle to the roadway and means for resetting the cradle to its raised position.
- 45 5. In a device of the class described, a cradle comprising an outer frame and a bottom or inner part both horizontally disposed and an upright rear portion, said bottom or
- inner part being so mounted and arranged that it will move vertically while remaining 50 in substantially a horizontal plane, means for automatically dropping the cradle to the roadway and means for resetting the cradle to its raised position.
6. In a device of the class described, a cradle comprising an outer frame and a bottom or inner part both horizontally disposed and an upright rear portion, said bottom or inner part being so mounted and arranged that it will move vertically while 55 remaining in substantially a horizontal position, means for automatically dropping the cradle to the roadway and means for resetting the cradle to its raised position comprising a curved foot lever guided by and 60 extending through a hole in the vehicle platform.
7. In a device of the class described, a cradle comprising a rear upright portion 70 and a horizontally disposed outer frame rigidly connected together and a bottom or inner part pivotally mounted on the front edge of the outer frame, means for automatically dropping the cradle to the roadway and means for resetting the cradle in its raised 75 position.
8. In a device of the class described, a cradle comprising a rear upright portion and a horizontally disposed outer frame rigidly connected together and a bottom or 80 inner part pivotally mounted on the front edge of the outer frame to have its rear edge free to move up and down with relation to the outer frame, means for automatically dropping the cradle to the roadway and 85 means for resetting the cradle to its raised position.

In testimony whereof I have signed my name to this specification in presence of three subscribing witnesses this 16th day of 90 March, 1918, at Chicago, Illinois.
